UNITED STATES PATENT OFFICE.

JOHN LOMA WILLIAMS, OF JACKSON, TENNESSEE.

IMPROVEMENT IN NUT-AND-BOLT FASTENINGS.

Specification forming part of Letters Patent No. 131,922, dated October 1, 1872.

To all whom it may concern:

Be it known that I, JOHN LOMA WILLIAMS, of Jackson, in the county of Madison and State of Tennessee, have invented certain new and useful Improvements in Fish-Plate Joints for Railway and other purposes; and do hereby declare the following to be a full, clear, and exact description thereof, reference being had to the accompanying drawing and to the letters of reference marked thereon.

The fish-bar joint now most generally in use is very defective, for the following reasons: Owing to the joints working loose, in consequence of the jarring caused by the trains, the ends of the rails become battered and dangerous; in time it becomes necessary to take up the rails for repairs, which invariably incurs heavy expense. Damage to engines and cars by reason of the sudden jolting caused by the impossibility of keeping the joints, under the present system, permanently screwed up. The danger to passengers resulting from the liability of the cars to be thrown from the track.

My invention obviates all the above-enumerated defects and secures a smooth, perfectly same, and uniformly-tight joint, which cannot work loose.

The nature of my invention consists in the combination of a fish-piece provided with an outer ridge extending the entire length, or merely around the bolt-holes of the same, and having screw-orifices and a screw-bolt provided with an opening in its end, within which is passed a split key, all as hereinafter more fully set forth.

The figures in the accompanying drawing, which forms a part of this specification, more fully represent my devices.

Figure 1 represents a perspective view of two sections of railroad rails with my mode of securing the same. Fig. 2 represents a section taken through one of the rails, showing the screw-bolt and fish-piece and the orifice in the end of the bolt where the split or twisted key is to pass through.

A A represent two sections of railroad rails with the usual fish-piece B on one side. C represents the construction of fish-piece used on the opposite side of the rails. Upon the outer side of this fish-piece is a rib or swell, a, which may be extended the entire length of the fish-piece, or may be only on those parts where the bolt is to pass through. This rib is formed

with the fish-piece proper. At suitable intervals this fish-piece, as well as the fish-piece B, is formed with circular openings for the screw-bolts to pass through. The orifices in the piece C are provided with female screw-threads, while the orifices in the piece B are not. D represents the ordinary screw-bolt, with the exception that its outer end is provided with a slot, as shown in Fig. 2, through which a split key, d, as shown in Fig. 1, is passed after the bolt has been passed through the piece B, rail A, and piece C.

In Figs. 1 and 2 of the drawing I have shown a set-screw, b, which is passed through a hole in the ridge a of the piece C, and extends down onto the screw-bolt D for holding the same tightly in its place; but I do not claim said device under this patent; neither do I wish to be understood as confining myself to the use of the same in connection with the other features of the invention.

The split key d may be either of spring steel or of such metal as to allow the prongs thereof to be bent outward after it is passed through the bolt.

By the invention herein described the fish-piece C, having screw-threads, acts in lieu of a nut, and the key prevents the bolt from becoming disengaged. By means of the ridge on the piece C I am enabled to pass the key freely through the slot in the bolt end, which would not be the case if the usual fish-piece is used and the key of sufficient length to properly perform its function, as the top of the rail would greatly interfere when the bolt is so screwed as to leave the slot perpendicular, or nearly so. Besides, it gives more hold for the bolts, and consequently greater strength to the joints.

Having thus fully described my invention, what I claim is—

The combination of the screw-bolt D with a slot in its outer end, the fish-piece C with screw-orifices and ridge a, and the key d, all substantially as and for the purposes set forth.

In testimony that I claim the foregoing I have hereunto set my hand on this 24th day of June, 1872.

JOHN LOMA WILLIAMS.
